UNITED STATES PATENT OFFICE

162,891

METAL-CUTTING SHEARS

Willie M. Shoffner, Dayton, Ohio

Application May 8, 1950, Serial No. 9,774

Term of patent 14 years

(Cl. D22—5)

To all whom it may concern:

Be it known that I, Willie M. Shoffner, a citizen of the United States, residing at Dayton, in the county of Montgomery, State of Ohio, have invented a new, original, and ornamental Design for Metal-Cutting Shears, of which the following is a specification, reference being had to the accompanying drawings, forming a part thereof, wherein:

Figure 1 is a perspective side elevational view of a metal cutting shears illustrating the design with handle portions shown in broken lines;

Figure 2 is a perspective elevational view as viewed from the right-hand side of Figure 1 and illustrating the shears in a more nearly closed position;

Figure 3 is a side view as viewed from the left-hand side of Figure 1;

Figure 4 is an end elevational view;

Figure 5 is a bottom plan view of the shears as shown in Figure 3;

Figure 6 is a top plan view of the shears as shown in Figure 3;

Figure 7 is a vertical cross-sectional view through the cutting blade of the metal cutting shears;

Figure 8 is a cross-sectional view taken parallel to the cutting blade to illustrate the cutting and forming block at the end of the metal cutting shears;

Figure 9 is a cross-sectional view like Figure 8 with the cutting block in the other of its two selective positions.

The dominant features of the design reside in the portions shown in full lines.

I claim:

The ornamental design for a metal-cutting shears, substantially as shown and described.

WILLIE M. SHOFFNER.
